WINDOW SASH CLAMPING DEVICE

Dewitt Tappan, Irondequoit, N. Y., assignor to
Ada I. Tappan, Irondequoit, N. Y.

Application July 24, 1950, Serial No. 175,580

3 Claims. (Cl. 292—140)

1

This invention relates to a window sash clamping device for securing a window sash or the like in any desired position for safety and ventilation.

An object of the present invention is to provide a window sash clamping device that permits opening a window by lowering the upper sash, or by raising the lower sash, or by both, and that will secure both sash against rattling or movement.

Another object of the present invention is to provide a window sash clamping device that presents a liberal clamping area to the surface of the sash against which the clamping pressure is applied and thereby avoid marring the sash surface.

A further object of the present invention is to provide a window sash clamping device that secures the upper and lower sash to each other and locks them together so that the selected total opening cannot be increased by forceable movement of both sash together from the outside of the window and thereby permit undesired entry through the window.

A still further object of the present invention is to provide a window sash clamping device with a minimum number of parts.

Still another object of the present invention is to provide a window sash clamping device with removable operating means thereby preventing children or unauthorized persons from changing the size of the opening.

Other objects, purposes and characteristic features of the present invention will be in part obvious from the accompanying drawings, and in part pointed out as the description progresses.

In considering the present invention in detail reference will be made to the accompanying drawings in which like reference characters are used to designate corresponding parts in the various figures and in which:

Fig. 1 is a sectional view of a portion of a window and the sash clamping device taken along the line 1—1 in Fig. 2 drawn to a reduced scale;

Fig. 2 is a plan view of the device attached to the upper cross rail of the lower sash of a window and applying clamping pressure against the vertical stile of the upper sash with the stile, jamb, parting strip and stop shown in section as viewed from the line 2—2 of Fig. 1;

Fig. 3 is a sectional view taken along the line 3—3 of Fig. 2;

Fig. 4 is a sectional view taken along the line 4—4 of Fig. 6;

Fig. 5 is a front elevation;

Fig. 6 is a plan view with the clamping member retracted;

2

Fig. 7 is a sectional view taken along the line 7—7 of Fig. 6;

Fig. 8 is a sectional view taken along the line 8—8 of Fig. 7;

Fig. 9 is a plan view of an alternate construction with the operating lever removed, and

Fig. 10 is a sectional view taken along the line 10—10 of Fig. 9 as it would appear if the operating lever were assembled.

In Figs. 1 and 2 are shown parts of a conventional window frame and window sash with the present invention applied thereto. 1 is the side piece of a window frame normally known as the jamb, 2 is the facing, 3 is the blind seat, 4 is the parting strip and 5 is the stop of the window frame, 6 is the cross rail of the upper sash, 7 is the upper sash glass, 8 is the stile of the upper sash, and 9 is the cross rail of the lower sash.

The window sash clamping device as embodied in the structure shown attached to the sash in operating position in Figs. 1 and 2 comprises two parts or members only exclusive of the fastening screws which also act as parts of the device. In this embodiment part No. 10 is the clamping member and part No. 11 is the operating cam. In the alternate structure, Figs. 9 and 10, part No. 16 is used instead of part No. 11 and an added part No. 17 is used. The following description applies to either structure except where the difference is pointed out.

The clamping member 10 is preferably constructed of sheet metal and is roughly an L-shaped piece before bending. It has a round hole suitable to serve as a bearing at the junction of the arms of the L, and slots 18, Figs. 2 and 6, formed parallel to the long arm of the L in suitable position to leave a flat pressure pad 19 after the short arm of the L is folded back to form a retaining lip 20. This structure is shown in Figs. 6 and 8. At each end of these slots a portion of the metal is left to secure the pad 19 and the lip 20 to the body of the member 10. This securing portion being reduced in cross section permits the lip 20 to spring out slightly to admit the cam 11 for assembly.

Cam 11 is also preferably constructed of sheet metal of a thickness similar to that of member 10. In the structure shown in Fig. 2 it has an arm 21 terminating in a flat upturned portion 22 suitable for turning the cam on its pintle. The body portion of the cam is circular in form except that portion forming the operating arm. Concentric with the outer periphery a disk 23, of suitable diameter to fit into the bearing in part 10, is punched out for a distance about equal to

or slightly more than the thickness of the member 10 but left secured to the body portion by spokelike portions 24 shown in Figs. 2 and 6 and in section in Figs. 7 and 10. At 15, Fig. 6, a hole is formed offset from the center and eccentric to the circumference of the disk for mounting the cam 11 directly on the top rail of the lower sash by means of screw 13, the body of which serves as a pintle on which cam 11 rotates as shown in Figs. 2 and 3. The outer periphery of cam 11 is of suitable size to bear against the pressure pad 19 as the outer surface of disk 23 rotates in its bearing in member 10. Thus it will be noted that cam 11 has two laterally disposed peripheries, concentric with each other but eccentric to the mounting screw and pintle 13, one of which bears against the pressure pad 19 and the other on the inner bearing surface of the hole in part 10, both of which apply effective clamping pressure.

An angular slot 25 is formed in the long arm of the clamping member 10. A screw 12 serves to secure part 10 to the upper surface of the top rail of the lower sash and also to act as a guide on which part 10 is free to slide back and forth within the limits of the slot 25. In Fig. 2 the window sash clamping device is shown in full lines in the position it is in when applying pressure against the side stile of the upper window sash. In broken lines it is shown in its retracted position. It will be noted that the movement of the clamping member is angular with respect to the window sash and that the angularity corresponds to that of slot 25. Thus the angular slot 25 and screw 12 serve to maintain the pressure pad 19 parallel to the surface of the upper sash stile 8 so that the surface of the same is not unduly marred by the window sash clamping device.

In Fig. 1 are shown screws 14 inserted at spaced intervals into the upper sash stile 8 and so placed as to be in the path of the pressure pad 19 as the window sash are operated in the window frame. The function of these screws is to form positive stops to prevent forceable opening of the window from the outside by slipping the pressure pad along the surface of the upper sash stile.

In operation, after the window sash clamping device has been properly attached, the cam is rotated by means of the pad 22, or the operating lever 17, in a direction to cause the clamping member 10 to travel toward the stile of the upper sash and apply sufficient pressure against the upper sash to hold both sash in the selected positions. To release the clamping pressure the cam is rotated in the opposite direction.

In the alternate construction, Figs. 9 and 10, cam 11 with its integral arm 21 has been replaced by cam 16 which is the same as cam 11 except that the integral arm has been removed and a socket 26 formed to admit a removable operating lever 17. This construction provides a window sash clamping device wherein the operating means may be removed and placed out of reach of children or other unauthorized persons. Otherwise this alternate construction is the same as that heretofore described.

From the foregoing it will be seen that I have provided a new and useful window sash clamping device that permits a sash adjustment to give a selected window opening at the top, at the bottom, or both, the operation of which does not unduly mar the sash surface, is simple in structure, easy to operate, and economical to manufacture.

While the invention has been described with reference to the structural details disclosed, it is not confined to this particular embodiment, and the application is intended to cover any modification or departures coming within the purposes of the improvements and the scope of the following claims.

1. claim:

10 1. A window sash clamping device of the character described comprising, a stepped cam having two laterally disposed concentric portions one of which is of greater diameter than the other, a bearing eccentric to said concentric portions, and means whereby said cam may be rotated; an attaching member having a portion thereof adapted to act as a pintle on which said stepped cam may have rotative movement and adapted to secure said cam to a flat surface with its smaller concentric portion adjacent thereto, 15 a clamping member having an opening therein comparable to the contour of the smaller of said concentric portions suitable to serve as a bearing in which the smaller concentric portion of said cam may have rotative movement, said clamping member being adapted to approach to and recede from an adjacent surface disposed at right angles to said flat surface to which said cam is secured on rotative movement of said cam, a pressure pad attached to said clamping member and disposed between the larger concentric portion of said cam and said adjacent right angle surface, a lip portion resiliently attached to said pressure pad and extending over the larger concentric portion of said cam and adapted to admit and retain said cam in its assembled position before said window sash clamping device is attached to a flat surface.

2. A window sash clamping device of the character described comprising, a stepped cam having two laterally disposed concentric portions one of which is of greater diameter than the other, a bearing eccentric to said concentric portions, and means whereby said cam may be rotated; an attaching member having a portion thereof adapted to act as a pintle on which said stepped cam may have rotative movement and adapted to secure said cam to a flat surface with its smaller concentric portion adjacent thereto, 40 a clamping member having an opening therein comparable to the contour of the smaller of said concentric portions suitable to serve as a bearing in which the smaller concentric portion of said cam may have rotative movement, said clamping member being adapted to approach to and recede from an adjacent surface disposed at right angles to said flat surface to which said cam is secured on rotative movement of said cam, a pressure pad attached to said clamping member and disposed between the larger concentric portion of said cam and said adjacent right angle surface, a lip portion resiliently attached to said pressure pad and extending over the larger concentric portion of said cam and adapted to admit and retain said cam in its assembled position before said window sash clamping device is attached to a flat surface, and means to retain said pressure pad approximately parallel to said right angle adjacent surface upon rotative movement of said cam.

70 3. A clamping device the construction of which is limited to two members exclusive of attaching screws comprising, a first named member consisting of a stepped cam constructed of sheet metal and having two laterally disposed concentric portions one of which is of greater diameter

75 tric portions one of which is of greater diameter

than the other the smaller of which comprises a circular portion punched out of said sheet metal concentric with the larger diameter and secured thereto by spoke sections bent to dispose said circular portion laterally with respect to the larger of said concentric portions, a bearing formed in said circular portion eccentric to said concentric portions suitable to cooperate with and rotate on the body portion of one of said attaching screws, and an operating arm extending from said greater diameter integral with said first named member; a second named member consisting of a clamping member constructed of sheet metal and having a circular opening there-in comparable to the contour of said smaller concentric portion suitable to serve as a bearing in which said smaller portion may have rotative movement, a pressure pad attached thereto and integral therewith disposed to contact said greater diameter of said cam, a lip portion resiliently attached to and integral with said second named member and adapted to admit and retain said cam in assembled position before said clamping device is attached to any flat surface by said attaching screws, and a slot in said second named

member adapted to receive one of said attaching screws; said second named member being adapted to be secured in operative position by said first named member when such member is secured to a flat surface by one of said attaching screws and to approach to and recede from an adjacent surface disposed at a given distance from said eccentric bearing in said cam and in a plane at right angles to the flat surface to which said cam is attached on rotative movement of said cam.
